WRENCH

Joseph A. Cogbill, Fanwood, N. J.

Application March 7, 1944, Serial No. 525,349

5 Claims. (Cl. 81—121)

This invention relates generally to improvements in hand tools; and the invention has reference, more particularly, to improvements in wrenches of the socket type.

The invention has for an object to provide a novel construction of wrench of the socket type having an annular head frame provided with a suitable hand lever or handle affixed thereto for extension therefrom, and novel means affixed to and within said head frame to form the angular orifice or polygonal socket of the wrench; thus providing a wrench construction requiring but a minimum of material in its make-up, and consequently one of low production cost, while nevertheless one of great durability and strength in use.

The invention has for a further object to provide a novel wrench structure wherein the means adapted to form the angular orifice or polygonal socket thereof comprises a plurality of sheet metal socket forming elements, each of which is bent to form a series of angularly related socket wall sections, whereby, when said elements are assembled within the surrounding annular head frame so as to be secured to and embraced thereby, the assembly will form an angular orifice or polygonal socket of desired shape; the socket wall sections as related to and engaged by the surrounding head frame, either per se or by associated means, providing a truss formation of great strength, whereby stresses and strains exerted upon the orifice or socket sides in use of the wrench are so distributed and absorbed that risk of deformation of the socket structure is eliminated.

Another object of the invention is to provide a socket wrench head comprising an assembly of elements so related as to provide a symmetrical reinforcing truss formation in support of the elements which provide the work engaging parts of the wrench; and wherein said work engaging parts may be variously shaped and disposed to cooperatively fit and engage particular kinds and shapes of work desired to be operated upon by the wrench.

Other objects of this invention, not at this time more particularly enumerated, will be understood from the following detailed description of the same.

Illustrative embodiments of the invention are shown in the accompanying drawings, in which—

Fig. 1 is a face view of one form of socket wrench made according to this invention; Fig. 2 is a side elevational view thereof; Fig. 3 is a transverse sectional view thereof, taken on line

3—3 in Fig. 1, but drawn on an enlarged scale; and Fig. 4 is an enlarged perspective view of one of the socket forming elements of the same.

Figs. 5 and 6 are respectively fragmentary face views of modified forms of socket wrench structure embodying the principles of this invention.

Fig. 7 is a face view of another form of socket wrench according to this invention; and Fig. 8 is a longitudinal sectional view thereof, taken on line 8—8 in Fig. 7.

Similar characters of reference are employed in the hereinabove described views, to indicate corresponding parts.

Referring to the drawings, the illustrative form 15 of the wrench according to this invention shown in Figs. 1 to 4 inclusive, comprises an annular head frame 10 provided by a circular metallic band or ring of desired wall thickness, height and diameter. Affixed to the outer surface of said head frame 10, for extension therefrom, is a hand lever or handle 11 of suitable length. Said hand lever or handle 11 is preferably provided with a widened inner end portion 12, the extremity of which is arcuately shaped to conform to the outer circumference of the head frame 10, when abutted upon the same. Said head frame and hand lever or handle are preferably united by welding the same together, thus forming a strong unitary structure.

30 The means to provide an angular orifice or polygonal socket within the head frame 10 comprises a plurality of sheet metal socket forming elements. These socket forming elements may vary in number and may comprise two or more, 20 and the same may be respectively shaped according to a given polygonal shape of orifice or socket desired to be formed by a given assembly thereof, or according to the form of truss structure desired to be furnished thereby.

40 In the arrangement of socket forming elements as shown in Figs. 1 to 4 inclusive, each comprises a body 13 of sheet metal of suitable thickness, length and width. Each said sheet metal body is formed, by means of suitable dies or other forming tools, into a generally arcuate shape but comprising a series of connected angularly related successive socket wall sections 14, forming one with another alternated included external and internal angles of 120°, whereby when said socket forming elements are assembled together end to end, the same will define two hexagonal orifices or sockets in angularly displaced relation one to the other.

45 Preferably two such socket forming elements 55 are provided, each of generally semi-circular

form, which, when assembled together in opposed relation, define a complete socket structure. It will be understood however that the socket structure formation may be produced from more than two arcuate elements, e. g., it may comprise three, four, six or more thereof. It will also be obvious that, in some cases, the complete series of angularly related socket wall sections 14 may optionally be produced unitarily from either a continuous or discontinuous sheet metal band or ring.

The socket formation, when produced as described, is sized to fit snugly within the annular head frame 10, so that the outer apices 15 of the angularly adjoined socket wall sections 14 will impinge upon the internal circumferential face of said head frame. When the socket forming elements are assembled and inserted within the head frame 10, said outer apices 15 of the angularly adjoined socket wall sections 14 are securely affixed to the head frame, preferably by welding the same thereto. Opposed meeting ends of said assembled elements are likewise securely joined together, preferably by welding. The height of the socket structure is preferably, but not necessarily, greater than that of the head frame, so that the respective open faces of said socket structure lie in planes outwardly offset from the respective face planes of the head frame.

It will be appreciated that the angularly adjoined socket wall sections, with their apices abutted against the external embracing head frame, mutually reenforce each other when selected faces thereof engage work to be manipulated, since said wall sections together with intermediate portions of the head frame form triangular truss like structures, whereby stresses and strains incident to manipulation of the work are resolved into those of tension and compression which are uniformly distributed and absorbed, and consequently a wrench head of great durability and strength is provided which is strongly resistant to injurious deformation in use.

The socket forming elements may be variously shaped to provide, when assembled, orifices or sockets of any selected peripheral shape, as, e. g., hexagonal, octagonal, square or of other desired polygonal form.

In the modified form of wrench according to this invention shown in Fig. 5, an arrangement and shape of socket forming elements is provided which is adapted to form a socket orifice of single hexagonal shape. Each said socket forming element comprises a sheet metal body bent to provide a series of connected angularly related successive full size socket wall sections 16. Said socket forming elements are assembled in opposed relation, to complete the hexagonal socket orifice, and then inserted within the head frame 10, so that the apices 17 of angularly adjoined socket wall sections impinge upon the internal circumferential face of said head frame, being secured thereto preferably by welding. In this construction, each socket wall section 16 is braced by a radial strut 18 interposed between the medial portion thereof and the opposing part of the head frame wall; these struts 18 are fixed in such relation preferably by welding their ends respectively to the said parts of the wall sections and head frame. It will be observed that this modified arrangement also furnishes a truss-like construction of great durability and strength.

Another modified form of the wrench of this invention is shown in Fig. 6. In this form, the socket orifice is of square shape, and is provided by opposed socket forming elements of right an-

gular shape to form angularly related socket wall sections 19. In this case also, the assembled socket forming elements are inserted within the head frame 10, so that the apices 20 of the angles thereof impinge upon the internal circumferential face of said head frame, being secured thereto preferably by welding. Each wall section 19 is braced by angular strut elements 21, the legs of which are footed upon the external sides of the socket wall sections 19, with their apices 22 impinging upon the internal circumferential face of the head frame 10, such contacting points being secured to these parts preferably by welding. It will be obvious that the angular strut elements 21 combine with the head frame and socket forming elements so as to provide a truss-like structure of great strength and durability.

It is sometimes desired to produce wrenches having special shapes of socket orifices adapted to correspond to and fit particular shapes of work desired to be manipulated by the wrench. An example of wrench construction, within the principles and scope of this invention, adapted to such end is shown in Figs. 7 and 8, wherein the same includes the head frame 10 and hand lever or handle means 11—12 extending therefrom. Inserted within the head frame 10 are truss-like socket forming elements providing a series of connected angularly related successive wall sections 23, the outer apices 24 of angularly adjoined wall sections 23 impinging upon and being secured, preferably by welding, to the internal circumferential face of the head frame 10. The socket defining means comprises an internal socket forming annulus 25, upon the external circumferential surface of which the inner apices 26 of angularly adjoined wall sections 23 impinge, and to which they are secured, preferably by welding. Secured to the internal circumferential surface of said socket forming annulus 25 are suitably shaped and spaced wrench lugs 27, which are arranged to correspond to and operatively engage a particular shape of work to which the wrench is desired to be operatively fitted for manipulation thereof. It will be observed, that this construction also provides a truss-like bracing structure for support of the socket defining means so that stresses and strains incidental to use of the wrench are uniformly distributed and absorbed, thus assuring a wrench of adequate strength and durability. It will be understood that many variations of form are possible of attainment in this type of wrench construction, the described form merely being by way of exemplification.

I am aware that various changes, in addition to those already mentioned, could be made in the above described constructions, and that widely different embodiments of this invention could be made without departing from the scope thereof as defined by the here following claims. It is therefore intended that all matter contained in the foregoing description and shown in the accompanying drawings shall be interpreted as illustrative and not in a limiting sense.

I claim:

1. A wrench of the socket type comprising an annular head frame having a hand lever affixed thereto for extension therefrom, and means disposed within said head frame adapted to form a polygonal socket orifice, said latter means comprising socket forming elements of sheet metal bent to provide a series of angularly related socket wall sections and assembled to define a socket orifice of desired shape, the apices of external angles of said socket forming elements being dis-

posed to impinge upon and being affixed to said head frame.

2. A wrench of the socket type comprising an annular head frame having a hand lever affixed thereto for extension therefrom, means disposed within said head frame adapted to form a polygonal socket orifice, said latter means comprising socket forming elements of sheet metal bent to provide a series of angularly related socket wall sections and assembled to define a socket orifice of desired shape, the apices of external angles of said socket forming elements being disposed to impinge upon and being affixed to said head frame, and pairs of angularly adjoined strut elements intermediate each socket wall section and said head frame and adapted to form truss-like reinforcement for said wall sections.

3. A wrench of the socket type comprising an annular head frame having a hand lever affixed thereto for extension therefrom, means disposed within said head frame adapted to form a polygonal socket orifice, said latter means comprising socket forming elements of sheet metal bent to provide a series of angularly related socket wall sections and assembled to define a socket orifice of desired shape, the apices of external angles of said socket forming elements being disposed to impinge upon and being affixed to said head

frame, and trussing means affixed to and between said socket wall sections and the head frame portions opposed thereto.

4. A wrench of the socket type comprising an annular head frame having a hand lever affixed thereto for extension therefrom, and means disposed within said head frame adapted to form a polygonal socket orifice, said latter means comprising a sheet metal formation bent to provide a series of angularly related socket wall sections arranged to define a socket orifice of desired shape, the apices of external angles of said formation being disposed to impinge upon and being affixed to said head frame.

5. A wrench of the socket type comprising an annular head frame having a hand lever affixed thereto for extension therefrom, and means disposed within said head frame adapted to form a polygonal socket orifice, said latter means comprising a sheet metal formation bent to provide a series of angularly related socket wall sections arranged to define a socket orifice of desired shape, the apices of external angles of said formation being disposed to impinge upon and being affixed to said head frame, and trussing means affixed to and between said socket wall sections and the head frame.

JOSEPH A. COGBILL.
